His Attorney.

UNITED STATES PATENT OFFICE.

WILLIAM R. BAILEY, OF LOS ANGELES, CALIFORNIA.

CURRENT-MOTOR.

1,317,538.

Specification of Letters Patent. Patented Sept. 30, 1919.

Application filed July 6, 1917. Serial No. 178,992.

To all whom it may concern:

Be it known that I, WILLIAM R. BAILEY, a citizen of the United States, residing at Los Angeles, in the county of Los Angeles and 5 State of California, have invented new and useful Improvements in Current-Motors, of which the following is a specification.

This invention relates to current motors and more particularly to current motors 10 adapted for installation in streams such as creeks, rivers, aqueducts and the like, and the invention has for its object to provide a motor of the character stated which will be relatively simple and inexpensive in construction and organization when its superiority in efficiency and durability are considered.

In accordance with the invention a divided scow is preferably provided and such scow 20 is arranged to have its main portion anchored or otherwise secured in position in a stream and a band, chain, belt or the like or a plurality of such band devices may be mounted for traveling about the other portion 25 of the scow, suitable sprockets or pulleys being provided to that end; the band device or devices may be provided with a plurality of spaced vanes which are mounted in such manner that they may "feather" on 30 the side moving against the stream and project laterally from the band devices to provide for the impingement of the water thereon as they are moved by the same. The sprockets, pulleys or the like, coöperating 35 with the band are mounted at the ends of the smaller scow portion against which the bands may lie, and such smaller scow portion preferably extends obliquely athwart the stream being united to the main scow 40 portion as by means of supporting members such as timbers applied at the upper portions of the scows and at the lower portions of such scows, suitable shafts for the sprockets or the like being provided. A channel for 45 the vanes as they are being returned upstream is provided between the scows, and a deflector is arranged at the bow of the main scow for directing water against the vanes as they successively round the forward end of the smaller scow portion. The 50 vanes are, as before stated, adapted to "feather" as they are returned upstream and the same are provided with suitable hinge means whereby connection is made 55 with the endless band or bands and such hinge means are arranged to permit feather-

ing when the vanes are drawn through the water by the band and provide rigid abutments for the vanes when the water is directed against the same to propel the band 60 or bands. The sprockets being secured to suitable shafts mounted in connection with the scows, power may be converted into electrical energy or other forms of energy to facilitate transmission to the shore or point 65 of use of such power or energy.

With the above and other objects in view the invention consists in the novel and useful provision, formation, combination, association and relative arrangement of parts, 70 members and features, all as hereinafter described, shown in the drawing, and finally pointed out in the claim.

In the drawings:

Figure 1 is a fragmentary plan view of 75 a current motor organized in accordance with the invention;

Fig. 2 is a side elevation of the showing in Fig. 1, and looking in the direction of the arrow near Fig. 1;

Fig. 3 is a plan view of a fragment of 80 one of the chains shown in the other figures, and upon an enlarged scale;

Fig. 4 is an enlarged fragmentary perspective view of one of the chains shown in 85 the other figures, and illustrating the hinge construction;

Fig. 5 is a sectional detail view of one of the sprockets, the view being upon a still further enlarged scale on the line x^5 of Fig. 90 1; and

Fig. 6 is a fragmentary sectional view taken on the line x^6 — x^6 , Fig. 1, upon an enlarged scale, and looking in the direction of the appended arrows.

Corresponding parts in all the figures are 95 designated by the same reference characters.

Referring with particularity to the drawing, in the embodiment of the invention therein shown, A designates a divided scow 100 comprising a main portion a and a secondary portion a' ; B designates an impulse-receiving element; C designates means for supporting the forward portion of the element B; D designates means for supporting 105 the rearward portion of the element B; E designates power transmitting mechanism, and F designates a deflector for directing fluid toward the element B.

The scow A comprising the portions a and a' is suitably formed to meet the requirement of any given installation, and the por-

tion a' is spaced from the portion a as by means of timbers or frame members 7 and 8 suitably secured to the scow portions to hold the same in assemblage and with the 5 scow portion a' spaced from the scow portion a to provide a channel 9 between the same, other frame members 10 and 11 being provided beneath the scow. The edge of the 10 scow portion a at the channel 9 ranges obliquely athwart the stream as at 12 and the scow portion a' lies parallel to such edge 12. The portion a' is formed to fill the space between the means C and D, being curved at its ends as at 13 and 14 to accommodate 15 the sprockets of the means C and D. At its sides 15 and 16 the scow portion a' is preferably flat and conforms to the path of the element B, the chains of which element are adapted to ride in channel irons 17 secured 20 as at 18 to the sides 15 and 16 of the scow portion a' . It will be understood that the scow portions are preferably arranged with side, end and top and bottom members so that each forms a box-like floating structure. 25

The element B comprises in the form of the invention shown in the drawing, a plurality of chains 19, certain links 19^a of which are provided with lateral extending abutments 19^b, and have pivot-receiving apertures 19^c provided in bosses 19^d arranged forwardly of said abutments, and a plurality of vertically disposed vanes 20 pivotally secured one to each link 19^a. The vanes 20 30 may be built up of wooden panels 20^a and hinge members 20^b, which hinge members are each provided with an orifice 20^c through which a pivot pin 20^d passes, such pivot pin likewise passing through the orifices 19^c of 35 the respective links 19^a, so that the vanes have a hinge-like connection each with a link 19^a. The hinge members 20^b are adapted to lie against the chains during certain 40 phases of movement of the vanes and to lie against the respective abutments 19^b during 45 impulse-receiving action thereby to cause movement of the element B. Three chains 19 are shown, but it will be understood that any number required in a given installation 50 may be employed, or flexible members other than chains, such as wire ropes or the like, may be employed in substitution for the chains. The supporting means C comprises a power shaft 21, and a plurality of sprockets 55 22, one such sprocket 22 being provided for each of the chains 19. The power shaft 21 is mounted at its lower end in a suitable bearing provided at the respective end of a timber 23 which lies along the lower surface 60 of the scow portion a' and projects beyond the curved end 13 of the same and such shaft 21 is mounted at its upper end in a similar bearing provided in an upper timber or member 24 which ranges along the upper 65 surface of the scow portion a' and projects

over the curved end 13, the shaft 21 extending through its bearing in the timber 24 and being provided at such projecting end with a beveled pinion 25. Each of the sprockets 22 is provided with teeth 22^a adapted to take 70 into chain links and each sprocket is provided at its sides with guide disks 22^b which may be secured to the sprocket as by means of bolts 22^c to assist in supporting and guiding the chains. 75

The supporting means D is arranged at the end of the scow portion a' opposite the supporting means C and comprises a shaft 26, and a plurality of sprockets 27 secured thereto, one such sprocket 27 being provided for each chain 19. The shaft 26 is journaled at its lower end in an overhanging end of the timber 23, a suitable journal bearing being provided, and the upper end of the shaft 26 is journaled in the overhanging end of the upper timber 24, a suitable bearing being there provided as at 24^a. The shafts 21 and 26 being so spaced, one at each end of the scow portion a' and the chains 19 rove about the respective sprockets 22 80 and 27, each chain 19 being rove about the pair of sprockets lying in its horizontal plane, the element B will be moved by the current and power may be taken from the shaft 21 through the pinion 25 and the means 85 E, which means is shown as comprising a rotatable shaft 28 suitably journaled as at 29 and mounted upon a timber or the like 30, and a gear 31 secured to the shaft 28 and meshing with the pinion 25. Near the 90 end of the power shaft opposite the gear 31 a pulley 32 may be provided and such pulley is adapted to transmit power to any suitable device by means of a belt 33 passed about the same. 95

The means F is shown as comprising a deflector 34 which is in the form of a shield extending into the water and arranged obliquely across the front end of the scow portion a and suitably secured thereto so that 100 water which would otherwise impinge on the scow is properly directed toward the vanes 20 on the impulse-receiving side element B. 105

The operation, method of use and advantages of the invention will be readily understood from the foregoing disclosure taken in connection with the accompanying drawing and the following statement: 110

The current motor being anchored as by 115 means of cables extending to the scow A or by means of piles driven in proper position to anchor the scow and permit the same to rise and fall with the level of a stream in which the motor is installed, the element B 120 being disposed obliquely transversely of the stream the water of the stream will impinge on the vanes 20 as they successively round the sprockets 22 and such impingement of water will cause the hinge portions of the 125 130

vanes, or the members 20^b thereof to abut against the respective abutments 19^b and thus propel the element B. As the vanes successively round the sprockets 27 at the 5 rearward end of the scow portion a' they will automatically "feather" or be presented edgewise to the water as they are drawn forward on the idle side of the chains 19 to be again brought into working position 10 after rounding the sprockets 22. The channel 9 accommodates the return movement of the vanes during feathering action. The deflector 34 is arranged to direct the portions of the stream directly ahead of the scow at or 15 toward the vanes so that the greatest possible power with a given installation may be obtained. By ballasting the box-like scow portions with water or other ballast the device may be submerged to the required depth 20 in a stream. The power generated by the stream acting upon the element B is transmitted through the chains 19 to the sprockets 22 and the power shaft 21, through the pinion 25 and gear 31 and through the shaft 28 25 and its appurtenances.

Having thus disclosed my invention, I claim and desire to secure by Letters Patent:

A current motor comprising a barge portion, a series of superposed and horizontally disposed endless chains, guide members carried by the barge portion and engaging the endless chains, corresponding links of the chains being formed with outwardly extending shoulders, vertically disposed shafts connecting the said links of the chains, hinge members applied to the shafts, and vertically disposed vanes applied to the hinge members, the before mentioned shoulders being arranged to limit the outward swinging movement of the vanes and hold them in impulse receiving position when moving in one direction. 30 35 40

In testimony whereof, I have signed my name to this specification in the presence of 45 two subscribing witnesses.

WILLIAM R. BAILEY.
